(57) **CLAIM**

The ornamental design for a display screen with transitional graphical user interface, as shown and described.

DESCRIPTION

FIG. 1 is a first image in a sequence for a display screen with transitional graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof; and,

FIG. 10 is the tenth image thereof.

The appearance of the display screen with transitional graphical user interface sequentially transitions between the images shown in FIGS. 1-10. The process or period in which one image transitions to another forms no part of the claimed design. The broken line showing of the display screen in FIGS. 1-10 forms no part of the claimed design. The broken line perimeter within the speech bubble in FIG. 10 is part of the claimed design. The broken line circle surrounding the left-hand icon in FIGS. 1 and 3 are part of the claimed design. The remaining broken lines illustrate portions of the transitional graphical user interface which form no part of the claimed design.
